UNITED STATES PATENT OFFICE.

THOMAS D. LOCKWOOD, OF MALDEN, MASSACHUSETTS.

ELECTRIC SIGNALING APPARATUS.

SPECIFICATION forming part of Letters Patent No. 249,147, dated November 1, 1881.

Application filed May 25, 1881. (No model.)

To all whom it may concern:

Be it known that I, THOMAS D. LOCKWOOD, a citizen of the United States, of Malden, in the county of Middlesex and State of Massachusetts, have invented certain Improvements 5 in Electric Signaling, of which the following is a specification.

My invention relates to an improved method of and apparatus for signaling upon telephone or telegraphic lines in cases where it is necessary to place a number of stations upon the same line or circuit.

It relates particularly to that class of electrical signals wherein the signaling device at 15 each station is included in a branch or local circuit, which at an arranged interval of time from the commencement of the operation is included in the circuit of the main line, or operated by the currents passing in said main line circuit, the interval of time differing for 20 each station on the line.

The object of my invention is to enable the operator at the central or principal station of such a line to sound a call or alarm at any 25 particular station required without putting in operation any of the others upon the line, and to effect this result in a simple, effectual, and reliable manner.

To this end my invention consists in a novel 30 method of operating from the central station the several mechanisms at the various stations, in order that the signal may be given at any particular station; and in certain novel combinations of apparatus at each station, including 35 the central station, whereby the required effect is attained.

My invention is based upon the fact that when the soft-iron cores of an electro-magnet are attracted to the respective poles of a permanent magnet and an armature placed near to those cores is provided with a strong spring, tending to draw it away, and that if the inherent magnetism of the permanent magnet is sufficient to overpower the spring, the armature 45 will be held down to the cores as long as no current passes through the coils, or when a current passes whose polarity is the same as the polarity of the permanent magnet; but when a current passes through the coil whose 50 polarity is opposite to that of the permanent magnet the magnetism is thereby weakened

or neutralized, and the armature is by the force of the spring drawn away.

The subject-matter claimed as new will be specifically designated in the several claims at 55 the end of this specification.

In the accompanying drawings, Figure 1 is a diagrammatic representation of an electric circuit fitted at each station with my apparatus, and showing the essential features of said 60 apparatus, both at the central and sub stations. Fig. 2 is a modification of the application of my invention, showing the signaling-instrument included in a branch circuit to earth. Fig. 3 is a second modification, showing how 65 the apparatus is applied to close a local circuit; and Fig. 4 is a detail of the form of magnet employed.

In the drawings I have represented at the central office, in addition to the transmitting 70 devices, a revolving apparatus and bell similar in every respect to those also shown as located at each sub-station. This is done that the operator, by watching the movements of the dial and index-hand of his own apparatus, may intelligently control the movements of the apparatus at each station. I therefore call the bell at the central station No. 1, the bell of the first sub-station No. 2, the second No. 3, and so on until the end of the circuit is reached. 75 I have shown the bell of No. 5 as being in its position of action, and the dials at the central station and at No. 2 as consequently presenting the figure 5 to the index-finger *f* at the top of the dial. The other stations are provided with similar dials; but for convenience of illustration those of stations 1 and 2 only are represented.

Referring for the present to Fig. 1, A is a side view of a permanent horseshoe-magnet, 90 which is shown in front view in Fig. 4. It is provided with soft-iron pole-pieces or cores *P*, which are preferably attached by passing a metal pin or bolt through the end of the permanent magnet and pole-piece. Surrounding 95 each soft-iron core is placed a coil of insulated wire, *a*, which is included in the line-circuit and forms a part of the main line.

It will be hereafter understood that the term "magnet," when used herein, includes the combination of permanent magnet, soft-iron pole-pieces, and coil.

Each magnet is fitted with, and by its inherent attractive power tends to draw down to its pole-pieces, a soft-iron armature, B, fixed to an armature-lever, l. This lever is pivoted at the center c, and at its outer end has a lug, e, which turns upward and serves normally to detain in any required position the metallic escapement or circuit wheel i, which is permanently fixed on the arbor h, and when released is rotated by any ordinary system of clock-work, which, forming no part of my invention, I have not considered necessary to describe.

Depending from an adjusting-screw, s, is a strong spiral spring, b, which is fastened to the armature and exerts thereon a constant force, tending to draw it away from the magnet. The magnet and spring at each station are so adjusted in relation to one another that the force exerted on the armature B by the spring b is slightly less than the attractive force exerted by the magnet A—that is, the two forces are so nearly balanced, but preponderating slightly in favor of the magnet, that the armature, while normally resting at or near the cores of the magnet, will yield to the force exerted by the spring, if that force is increased, even in a small degree, or if the opposing attractive influence of the magnet be in a small degree diminished. The tension of the spring b can be adjusted by turning the screw s, and the magnet can be adjusted very delicately by means of the device shown in Fig. 4, where the magnetic strength in the cores is regulated by means of a cross-piece of iron, q, which is placed across the legs of the permanent magnet, and which can be moved up and down and fastened at any desired point by the screw w. The nearer it is placed to the end of the magnet the less will be the magnetic effect upon the soft-iron cores inside the coil. A set-screw, C, limits the upward movement of the armature-lever.

The escapement-wheel i of each apparatus in the circuit is furnished with square teeth, corresponding in number to the stations on the circuit. These are placed at a suitable distance apart on the periphery of the circuit or escapement wheels, and in each case one tooth, j, of the series is composed of non-conducting material, which is inserted into the substance of the metal escapement-wheel i. This non-conducting tooth j is, of course, differently placed at each station in the circuit, as shown in the drawings, where the central-office wheel has its insulating-tooth placed as the first tooth of the series. In station No. 2 it is the second tooth, and so on. The material of which this tooth is formed also extends forward for a short distance toward the base of the tooth in advance, so that when the lug e of the lever l strikes the insulating-tooth in any instrument it shall not touch the metallic part of the wheel at any point. This is essential for a reason which will hereinafter appear.

65 Each circuit or escapement wheel is also provided with an extra tooth, u, set at a dis-

tance from any of the others, and when the circuit, with its several apparatuses, is not being used, the lug e of each lever will be elevated and rest against the tooth u. This tooth 70 u affords a convenient point at which each wheel may come to rest, so that after each revolution all the wheels shall be in unison with one another, and that at the commencement of a second revolution the tooth u shall 75 be the initial point from which all the wheels start.

Fixed upon the axis h of the escapement-wheel i is an indicating-dial, g, which is numbered, and which revolves with the wheel and 80 shows when the line is in use, and also which station is using the line, by presenting the number of such station to the index-finger n, which in each instrument is fixed at the top of the ring f, surrounding the dial. It is obvious 85 that when the line is at rest the pointer or index-finger n will be opposite the figure 1.

D is a vibrating bell connected in a branch or shunt circuit around the escapement-wheel, the magnet of which must be of sufficiently 90 high resistance to preclude a sufficient amount of current passing through its coil to vibrate its armature and bell-hammer, except when the shunt on short circuit through the wheel is broken.

k k' are ordinary reversing circuit-closing keys, connected respectively to the line and ground. The back contact or bridge, y, is connected with one pole of battery L. The front contact or anvil, y', of key k is connected with the 100 opposite pole of the battery, and the front contact or anvil, y'', of key k' with an intermediate plate, so as to divide the battery. When k is depressed the entire battery-current of given polarity is transmitted to line. When k' is depressed a portion only of the battery is connected, and a much weaker current of opposite polarity is sent to line. The keys, when not being operated, form, by their metallic back contact or bridge, y, the continuation of 110 the line to the ground. The line-circuit commencing at the ground G is through the keys to the coil of the magnet. After leaving the coil it is connected through the metallic supports, or in any suitable manner, to the armature-lever l, and from thence divides at the point 6, the main line being through the lug e of the lever l to the metal escapement-wheel i; thence through the frame of the instrument to wire 4 and out to the next station. The branch or 115 shunt-circuit line, diverging at point 6, leads to the vibrating bell, after which it is led by the wire 3 to the main wire 7, from thence out to the next station, where the connections are made in the same manner, and at the end of the circuit the line is, as usual, connected to the ground G'. A short conducting-wire, z, is led from the limit-screw C to the outer binding-screw of the vibrating bell D. In the normal condition 120 of the line all the armatures B are attracted by the magnets A, and the lugs e, engaging with the unison-tooth u of the escapement-

95 105 110 115 120 125 130

wheels, prevent their revolution. All the signaling-bells are thus cut out or short-circuited by the route of low resistance through the armature-lever *l* and escapement-wheel *i*, thence 5 passing to the metallic frame, and out by wire 4, and the zero-mark of each dial will be opposite the needle or index-finger *n*.

The operation of the apparatus will be readily understood with little additional explanation. 10 Suppose, for example, the operator at the central station wishes to signal station No. 5, as represented in the drawings. He presses the key *k'* once and holds it down. This connects a portion of the battery, thus sending to the 15 line a weak current of a polarity in opposition to the polarity of the permanent magnets at each station on the line. The magnetism of each magnet *A* is thus weakened or neutralized, and is no longer able to hold the armature *B* against the retractile force of the spring *b*, which immediately draws each armature upward with considerable power. This movement is communicated to the lever *l*, which has its center of motion at 6, and correspondingly 20 depresses its outer end, disengaging the lugs *e*, and allowing each escapement-wheel to rotate under the influence of its motive power in the direction of the arrow. The wheels at each station work synchronously with one another, 25 and when the operator at the transmitting-station observes by his own dial *g* that the figure 5 has rotated until it is opposite to the index-finger or pointer *n* he releases his key *k'*. The armatures *B* will then yield to the influence 30 of the permanent magnets, which are no longer neutralized by an opposing current, and be attracted to the cores, thus elevating the outer end of the lever *l*, and engaging by its lug *e* the fifth tooth of each escapement-wheel 35 on the circuit. The circuit will then be substantially in its normal condition, except that each wheel will have advanced to its fifth tooth, and that the fifth instrument in the circuit has, owing to the fact of its fifth tooth being 40 made of non-conducting material, broken the short circuit round its bell, and the fifth bell is thus included in the main line. The operator then presses his other key, *k*, which, connecting the entire battery, sends to line a strong 45 current of a polarity agreeing with the polarity of the several permanent magnets. This, of necessity, passing through the magnets of the vibrating bell *D* of the fifth station, rings it loudly, none of the other bells ringing, because 50 no other is in circuit, and none of the armatures *B* moving, because the magnetism of each permanent magnet is strengthened, instead of weakened, by the passing current, which now agrees in polarity with the polarity of the 55 magnet.

To prevent any of the bells ringing while the armatures are retracted and the wheels revolving, the short circuit being thus broken, the branch wire 2 is led from the back limit-screw, *c*, of each instrument to the out wire 3 of the vibrating bells, thus forming a second short

circuit as soon as the first through the wheels and frame is broken. This device serves also the purpose of keeping the resistance of the circuit practically uniform by keeping the additional resistance of the several bells out of circuit while the revolution of the wheel is in progress. The material of the insulating-tooth *j*, as previously stated, is also extended for a short distance in advance on the periphery of 70 the wheel, as seen in No. 5, so that all danger of contact between the lug *e* and the metallic substance of the circuit-wheel shall be prevented and the current confined to the bell desired to be rung. 80

The bell-hammer may be vibrated either by an absolute make and break of the circuit or by an auxiliary shunting device, which alternately includes in and excludes its own magnet from the circuit. 85

The modification shown in Fig. 2 is operated in substantially the same manner, but the circuits are differently arranged, and the details of the apparatus are also slightly different. In Fig. 2, which illustrates this modification, 90 I have represented the apparatus of one station on a circuit fitted with my apparatus. This apparatus differs from that before described only in that the escapement-wheel *i* is entirely made of some insulating material, such 95 as hard rubber, with the exception of the tooth corresponding to the number of the station. This tooth is a conductor, and is in metallic connection with the metallic axis or arbor of the wheel, and thus, through the frame-work 100 of the apparatus, to the bell *D*. Entering from the left and proceeding in the direction of the arrow, the main circuit is through the switch *Z* to the coils of the magnet *A* and out toward the right. A short wire connects the 105 main line, after it leaves the magnet-coil, to the armature-lever *l*, and there normally ends; but when the circuit is operated in the before-described manner the escapement-wheel *i*, in common with the other wheels on the circuit, 110 rotates until the number of the station desired is opposite the index, where it stops by the re-engagement of the lug *e* with the wheel, by which engagement the branch circuit is also completed through the conducting-tooth and 115 axis of the non-conducting wheel, and through the bell *D* to earth, cutting off temporarily the remainder of the main circuit. In this case, between the last magnet-coil on the circuit and the terminal ground, must be inserted a 120 resistance greater than that of the coil. I have also shown the transmitting-keys and battery in this drawing, and by connecting them in the manner delineated at each station on the line I may, if I so prefer, give any or all 125 of the stations the power of individually calling any other station, although I prefer to give such power to the central station alone. The keys are normally kept out of circuit by the switch *Z*, which must be thrown off when the 130 keys are to be operated.

The modification shown in Fig. 3 represents

the application of my invention to signaling by closing at the desired station the circuit of a local battery, which includes a bell, and thus causing the alarm to be sounded by said bell.

5. The operation is similar in every respect to those hereinbefore described, and the same battery used to operate the transmitting-telephone may be employed to ring the bell.

I do not desire to confine myself to the particular construction and arrangement of circuits herein shown and described, as these may be greatly varied without departing from the principle of my invention, and many modifications will readily suggest themselves to persons skilled in the art. I may, for example, improve the electrical connection between the escapement-wheel and the armature-lever in Fig. 1 by fixing on the same axis as the wheel a conducting-disk having an insulated surface at one point of its periphery corresponding to the insulated tooth on the wheel, and a frictional conducting-spring bearing on said disk.

It is essential, for the proper working of my invention, that each consecutive compound permanent magnet A shall be so connected in the circuit that their polarity shall at each station be the same, and oppose the polarity of current sent when the key is pressed, which connects the smaller amount of battery to line. This is readily done in practice by any person who is ordinarily experienced in the art of telegraphy; for if, on connecting any station, it be found that when the current from the smaller battery is sent to line, instead of neutralizing the magnet and freeing the armature the magnetism is increased, it is merely necessary to reverse the connecting-wires at such station, which operation will give the required direction of current.

To connect the magnets properly it would readily become a matter of routine to have the binding-screws of the apparatus so marked that the person connecting the instruments would at once understand that the binding-screw marked, for example, G must always be connected to the line from the central station, and that the line toward the ground end must always be connected to the screw marked E.

I am aware that signaling-bells have been heretofore operated individually by including them in a shunt-circuit which at the will of the operator is closed or broken by the action of an electro-magnetic escapement, such a device being shown in Letters Patent granted to S. W. Francis, No. 219,244, September 2, 1879.

55 I am aware, also, that such bells have also been operated by connecting them in the earth branch, which is connected and disconnected at will. I consequently do not broadly claim any such device; neither do I claim as a new invention the special form of electro-magnet which I employ, as it is old; but

What I do claim is—

1. An individual signaling apparatus consisting of a compound permanent magnet provided with soft-iron cores, helices forming part of the main-line circuit, an armature and le-

ver, and a retractile spring, in combination with an electro-magnetic call-instrument in a shunt, ground branch, or local circuit, a rotary circuit-changer or switch controlled by the compound magnet, and operating to bring said call-instrument into position to sound the alarm, and serving also as an escapement-wheel, and an auxiliary branch circuit, normally open, but adapted to close and short-circuit the call-instrument by the action of the armature-lever during the period of revolution of the rotary switch.

2. In an individual signaling apparatus, the combination of an electro-magnetic call-instrument controlled and brought into and out of position to sound the alarm by an escapement-wheel which acts as a switch, and the trip-motion comprising a permanent magnet, with helices on its poles, and an armature, and operating to release said escapement-wheel when a current of given direction is on the line-circuit, and to engage and detain it when no current is upon the line, substantially as described.

3. In an electric circuit, the combination of a series of electro-magnetic signaling-instruments, each normally cut out of circuit, and a series of rotary switches or circuit-changers, acting also as escapement-wheels, and adapted to include any desired bell in the main circuit, or in position to sound the alarm, each rotary switch being controlled by the armature-lever of a compound permanent magnet, which, when no current is upon the circuit, engages with and detains the escapement, the armature being attracted by the permanent magnet, but which, when a current traverses the line in direction opposing the polarity of said permanent magnet and neutralizing the same, thus causing the armature to withdraw, releases the escapement and permits the switch to rotate, substantially as and for the purpose set forth.

4. The combination of a circuit-changing armature-lever, l, adapted to break the short circuit round an electro-magnetic signaling-instrument and instantly re-establish a short circuit by making contact with the branch wire 2, with the compound permanent magnet A, the signaling-instrument D, the rotary circuit-changer i, the shunt-circuit 3, and the branch circuit 2, substantially as described.

5. The combination, in a system of electrical signaling, of the compound magnet consisting of the permanent magnet A, coils a, soft-iron pole-pieces P, armature B, armature-lever l, and retractile spring s, the signaling-keys k k', the battery L B, the electric escapement i, normally forming part of the main circuit, the bell D, the shunt-circuit including said bell, and the branch circuit 2, substantially as described.

6. The combination, in an individual signaling-instrument, of the compound permanent magnet A, with a rotary switch, adapted also to operate as an escapement, and a signaling-instrument included in local branch or shunt

circuit, substantially as and for the purpose set forth.

7. In an individual signaling-instrument, the combination of the compound permanent magnet A with a rotary switch, *i*, adapted, also, to operate as an escapement, and a signaling-instrument in a local branch or shunt circuit, and adapted to be brought into position for operation, when desired, by the engagement of the armature-lever *l* with a given

tooth, *j*, in the rotary electric switch *i*, substantially as set forth.

In testimony whereof I have signed my name to this specification, in the presence of two subscribing witnesses, this 23d day of 15 May, 1881.

THOMAS D. LOCKWOOD.
